UNITED STATES PATENT OFFICE.

EDWIN R. MERRILL, OF COLUMBUS, OHIO, ASSIGNOR TO JOSEPH A. JEFFREY, OF COLUMBUS, OHIO.

MINING-MACHINE.

No. 870,116.

Specification of Letters Patent.

Patented Nov. 5, 1907.

Application filed April 7, 1898. Serial No. 676,813.

To all whom it may concern:

Be it known that I, EDWIN R. MERRILL, a citizen of the United States, residing at Columbus, in the county of Franklin and State of Ohio, have invented certain 5 new and useful Improvements in Mining-Machines; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

Figure 1 is a side view of a mechanism embodying my invention. Fig. 2 is also a side view, showing the 15 principal parts of the machine on a larger scale when in the position relatively to the ground line, where it is ready for transportation. Fig. 3 shows in top, plan view the parts in Fig. 2, except that the supporting columns are in section. Fig. 4 is a rear elevation of the 20 machine on a still larger scale. Fig. 5 is a vertical section on the line x , x of Fig. 2. Fig. 6 is a cross section on the line y , y , Fig. 2. Fig. 7 is a vertical longitudinal section on the line 7—7 Fig. 6. Fig. 8 is a horizontal section on the line 8—8 Fig. 2. Fig. 9 is a 25 detail view. Fig. 10 is a horizontal longitudinal section of part of the mounting for the rear end of the central thrust bar K of the chain frame. Fig. 11 is a detail view. Fig. 12 is a detail longitudinal sectional view 30 illustrating the coupling uniting the two parts of the adjusting shaft q .

The essential parts of the machine comprise a longitudinal frame, or bed adapted to be made temporarily stationary, a carriage frame adapted to move forward and back on the bed, and a vertical frame, or a series 35 of columns adapted to support at one position or another both the bed and the carriage.

The bed consists of the side bars A, A extending longitudinally and situated along the sides, the cross girders a and the front and rear cross parts a and a^2 . The 40 parts a extend downward along the sides of the bars A and to points considerably below them, and then across from side to side, as at a^3 . At the bottom these bars a , a^3 have secured to them longitudinally arranged bars a^4 which not only serve as braces, but also as 45 shoes or supports for the machine when it is upon the ground. The front cross frame, consists preferably of upward and inward inclined bars a^5 which at their lower outer ends are secured rigidly to the side parts of the bed and at their inner ends carry a guide a^6 . 50 Preferably I form the bars a^5 and the guide a^6 integrally together. Two or more of the cross girders a are formed with or have secured to them bosses b , from which there project outwardly spindles or stub axles b^1 ; and upon the latter are mounted detachable wheels B.

The latter may be flanged or smooth-faced to permit 55 them to run upon a track, or upon the ground.

The carriage is fitted to and rests upon the bed frame thus generally described. This carriage is formed of a motor and gearing carrying part and a cutter carrying part. At present I prefer to employ a cutting apparatus of the endless chain sort; and hence the cutter carrying part of the carriage is a device adapted to support, guide, and advance the chain which carries the cutters.

The part of the carriage which supports the motor 65 or engine and the gearing is indicated as a whole by C, it being in the mechanism illustrated a platform or plate. It rests upon the inwardly turned flanges a^7 of the longitudinal side bars A of the bed frame.

D indicates the motor. That shown is an electric 70 motor. It may be of any suitable form, but I prefer one substantially as shown and having its parts arranged in the following manner. Its armature shaft d extends longitudinally of the machine and is provided with a pinion d on the front side of the motor, the field 75 magnets being supported upon brackets D' secured to and rising from the platform or plate C. The armature pinion d engages with a large gear wheel E, which is secured to a shaft e arranged longitudinally of the machine and lying partly under the motor and 80 extending to points in front thereof. At its forward end this shaft carries a bevel pinion E' for actuating the cutter chain, and at its rear end it carries a worm E² for driving the carriage advancing mechanism.

The bevel pinion E' engages with a bevel wheel F on 85 a shaft f. This shaft is mounted in brackets or standards F', F² which are secured to and rise from the platform or plate C. It carries also a sprocket wheel F³ for driving the cutter chain, and a worm F⁴ for actuating the carriage withdrawing, or pull-back mechanism. 90

The worm E² above referred to, on shaft e engages with a worm wheel G on a carriage moving shaft g . The worm F⁴ above mentioned engages with a worm wheel H on a shaft h, arranged longitudinally of the machine, and extending back to the shaft g , and at its rear end 95 carrying a worm H' which engages with another wheel G', on the shaft g .

The wheels G, G' are both loosely mounted on the shaft g , but the one or the other can be connected therewith by means of a clutch I having teeth or projections 100 adapted to engage with these wheels, the clutch being splined or feathered to the shaft g . The wheels G and G', can rotate continuously, but in opposite directions and with different speeds. The shaft g also has two other wheels or pinions J, J, but these are rigidly secured to it. They engage with the teeth j of the racks J' which are formed on or rigidly secured to the side bars A of the bed frame. 105

When the pinions J, J, and shaft *g* are being actuated by the worm wheel G they are slowly rotated in the direction which feeds the carriage forward. When the clutch I however is moved over to engage with the 5 other worm wheel G' the shaft *g* and the pinions J will be rotated in the opposite direction and with a higher speed to pull the carriage back.

The chain frame consists of a central bar K, with a front cross-head K', and, by preference, the inclined 10 bracing and guiding bars K². At the rear end this chain frame is supported from the platform or plate C by means of the bracket or standard K² which is so arranged and is so connected to the chain frame as not to interfere with the free travel of the cutters. The parts 15 K, K' and K² are arranged in vertical planes, and not horizontally as in undercutting machines, and consequently the cutter chain L travels in vertical planes, the latter being also the vertical planes of the sprocket wheel F³, see Fig. 3. The bar K is supported in the 20 guide a⁶ above described, which is rigidly secured to the bed frame. The cross head K' is in front of the guide and cross frame a', and one of the parts K² is above the guide, and the other below it, lying in the open space between the inclined bed bars a⁵; and consequently 25 the front guide a⁶ and its carrying bars a⁵ present no obstruction to the chain frame, which can travel forward until the sprocket wheel F³ nearly reaches the guide. The parts K², K² are angular chain guides, shown in cross section at Fig. 5.

30 It will now be seen from the drawings and the above description that I provide for making a cut in coal or similar material which shall be narrow (three or four inches) horizontally, but wide (three or four feet) vertically. In other words the cut formed by the machine is a "shear" cut.

Where the vein of coal is narrow vertically a single cut will be sufficient—that is on a given vertical line. But in many places it is desirable to form such a shear cut over a vertical line of six or more feet. Hence it 40 becomes desirable to support the machine in either of two or more positions vertically. This I accomplish as follows. M, M are columns or uprights, one adapted to be placed on each side of the machine. Preferably they are hollow, as shown in Figs. 2, 4 and 8. They 45 are adapted to be firmly bound or clamped in position between the roof and floor of the mine by means of a screw rod *m* engaging with a nut *m'* having a hand wheel *m*², with a nut bearing against the upper end of the tube M. Preferably the upper and the lower ends 50 of the rod *m* and the column M are pointed, as indicated at *m*³, *m*⁴ so that they can be driven in the opposite walls of the mine, as the roof and the floor. At the lower ends of the columns a connecting bar or plate *m*⁵ can be used to properly space and brace them. Upon 55 the inner side of each column M there is a vertically arranged rack O either integral with or secured to its column.

The bed-frame is adjustably secured to each of the 60 columns M M as follows. N indicates a clamping device. It is composed of an inner and an outer part, the inner having a ring segment *n*, and the outer a companion segment *n'*. The outer part has hinge ears *n*³, and the inner a counterpart ear *n*⁴, which is connected to those at *n*³ by a pintle *n*⁵. These two ring segments *n*⁶ can be drawn together so as to attain a powerful grip

upon the column M by means of a bolt at *n*⁶ which is hinged in ears *n*⁶ upon one of the segments and carries a nut *n*⁹ which bears against an opposing ear *n*⁷ on the other segment. The ear *n*⁷ has a slot *n*¹⁰ through its edge by which the nut can be quickly disengaged entirely 70 from the ear so as to permit rapid attachment and detachment of the column. The inner segment carries also an inwardly projecting bracket *n*² which is connected to a plate *n*¹³ that can be connected in any suitable manner to the bed-frame of the machine. P is a 75 pinion engaging with the rack O, and carried by a shaft *p* which is mounted in the bracket *n*² in bearings at *p*'. The pinion may be rotated for the purpose of elevating or lowering the bed upon the columns by any suitable mechanism. As shown, the shafts *p* extend 80 backward from the columns to points near the rear of the bed where they are held in suitable bearings. Each shaft *p* has a worm wheel Q, and through these worm wheels a cross shaft *q* is connected to the shafts *p* *p* by means of worms Q' each engaging with one of 85 the worm wheels Q. The shaft *q* can be rotated by a crank such as at Q² (Fig. 3) or by other suitable device, as for instance a lever Q³ such as shown in Fig. 1, connected to the shaft *q* by a ratchet and dog.

When the shaft *q* is rotated in one direction it, 90 through the above described gearing, and the shafts *p* rotate the pinions P in such way as to elevate the bed-frame and cutting apparatus to any desired point, as is shown in full lines in Fig. 1. By turning the shaft *q* in the opposite direction they can be again lowered, as 95 illustrated by the dotted lines in Fig. 1. At the times when the machine is being thus adjusted vertically upon the upright frames or columns, the clamps at N are loosened to permit the free movement. After the desired position, vertically, has been reached, the 100 clamps are again set up with the utmost firmness.

To assist in supporting the mechanism at any position vertically, use may be made of detachable stops or holders which can be inserted as desired into apertures or seats M³ in the columns, as shown in Fig. 1. 105

The center of efficiency of the supporting devices at N is arranged approximately in the transverse line of the center of gravity of the entire machine when the carriage is drawn back to its rear limit. That is to say, the columns M M and their connecting devices are so 110 arranged that practically the entire weight (say 2,000 pounds) is taken upon them. This enables me to provide a very simple, effective and readily operated mechanism for accomplishing the vertical adjustment, in contradistinction to the more complicated and less 115 easily handled devices that would be necessary if the weight of the mechanism was carried at a greater number of supporting points.

The front end of the machine is held and steadied by 120 a supplemental frame secured to the bed and also consisting preferably of two columns S S suitably connected together. As shown, each of these comprises a lower tubular part s terminating in the bottom in a pointed foot s', and a threaded extension rod s² adapted to engage with the roof. s³ is a nut engaging with the 125 part s² and bearing downward upon the part s and having a hand wheel s⁴ by which the nut can be turned and the column tightly bound in place, or loosened. Each of these columns S is connected to the bed-frame at points suitably near the front end, preferably at one 130

of the front corners. It is provided with a clamp T having an outer segment and an inner segment t t' hinged together at t^2 and provided with a hinged set bolt t^3 engaging with a slotted ear. The clamp T as a whole is connected preferably loosely to the bed-frame, it having a pintle at t^4 which fits in a sleeve t^5 rigidly connected to the bed-frame, preferably being formed integral with the cross frame a' above referred to. These columns S S as above said, provide a bracing and steady mechanism for the front end of the machine. But when vertical adjustment of the entire machine is being effected, they present no binding or clamping, for after the clamps at T T are loosened, the front end of the machine will readily move up or down because of its weight being balanced or carried upon the rear main columns M M. And the loose connection at t^4 t^5 provides for independent movement of the columns S S as to each other, so that they can be set as desired.

By having a vertical frame or set of columns of the character described, not only can the machine be supported or suspended and adjusted readily in the way described, but provision can be made for setting the different columns or parts constituting the frame independently of each other. The right-hand side of the machine can be adjusted independently of the left, and vice versa. For this purpose I prefer the arrangement of parts shown in Fig. 12 in connection with the adjusting shaft q. In the structure illustrated, this shaft is made in two parts q^4 q^5 which can be connected together or rotated independently of each other. As shown, they are connected by having heads q' q'' at about the center transversely of the machine, and these heads are inclosed by a sleeve R. One or both of the heads can be provided with pin-holes r, and a detachable pin r' can be employed passing through the sleeve R and adapted to enter one or the other of the pin-holes r in the head. When one side of the machine is to be lifted or depressed independently of the other, the pin r' is withdrawn, and then that part of the shaft q (either q^4 or q^5) which is connected with the pinion P on the side to be adjusted is rotated as above described, whereupon its side of the machine will be raised or lowered, while the other remains stationary.

The chain frame K K' K² is adjustably connected to the engine platform or plate as follows. U is a vertically arranged plate with a guide-way which receives a bracket U' secured to and extending laterally from the center bar K of the chain frame. This bracket U' carries a cross bar V which has a threaded aperture v, a head v', and a nut v³. The bar V fits in a slot u in the guide-plate U and passes through an aperture in the bracket U'. W is a screw-rod threaded to engage with the bar V and mounted longitudinally across the slot u. Its inner end is situated in a socket at w' in the platform standard or plate U, and at its outer end it has a collar w which is held in a seat by means of a detachable plate U². The outer end of the screw-rod, as at w², is adapted to receive a wrench or tool for rotating the rod. When it is rotated, it moves the cross-bar V forward or back toward or from the shaft f and the axis of the sprocket wheel F³, and as this bar V moves thus forward or back, it carries with it the bracket U' and the chain frame through its bar K; and consequently the tightening or loosening of the

chain can be readily effected. At the times of such adjustment, the nut at v³ should be loosened on the bar V, this nut v³ being a clamping device which binds the cross bar V to the platform upright or plate U, and this binding or fastening of the cross-bar V relieves the bolt W and its threads of all strain from the cutting mechanism and from the weight of the parts.

Any suitable mechanism may be employed for shifting the clutch I. For illustration I have shown in the drawings a mechanism like the one disclosed in my Patent No. 798,201, to which reference is made for a more detailed description. In Fig. 11 x indicates a vertically arranged shaft, mounted at its ends in bearings carried by the under wall of the motor case, and the platform C, respectively. x' is a toothed wheel secured to the shaft x and arranged to mesh with the series of ribs i on the clutch. x² is a hand lever secured at its inner end to the shaft x and adapted for rotating the shaft to shift the clutch. y is a lever pivoted so as to swing about the axis of the shaft x. It carries a toothed plate y' which also meshes with the ribs i on the clutch. This lever y is intended to be operated automatically in any well known manner, as for example as illustrated in my above referred to patent, to shift the clutch during the operation of the carriage along the bed.

What I claim is:

1. In a mining machine, the combination of a reciprocating carriage having a chain frame arranged vertically between the sides of the carriage, a cutter chain on said chain frame adapted to cut a vertical slot narrow horizontally but elongated vertically, a bed frame for the carriage extended laterally horizontally and having substantially parallel side bars for guiding the carriage and adapted to lie in substantially the same horizontal plane, the vertically arranged supporting devices for the bed comprising columns at the sides of the frame and adapted to be secured to the roof and floor, and means for vertically adjusting the bed frame upon the vertical supporting devices, substantially as set forth.

2. In a mining machine the combination of a reciprocating carriage, a chain frame on the carriage arranged in vertical planes between the side bars of the carriage, a cutter chain on said frame adapted to operate at the front end of the machine, a motor on the carriage at the rear end and traveling therewith, a rectangular bed frame for the carriage extended laterally horizontally and having substantially horizontal parallel side bars for guiding the carriage and a vertical support for the bed arranged to provide a ground support therefor comprising two independent columns independently fastened to the floor and to the roof, one upon each side of the bed frame and situated in the transverse plane of the center of gravity of the whole mechanism when the carriage is in its rearmost position, substantially as set forth.

3. In a mining machine, the combination of the bed, the carriage moving thereon, the cutter frame on the carriage, the vertically arranged columns, adapted to be secured independently of each other to the roof and to the floor of the mine and situated at fixed points adjacent to the bed, one on each side thereof, vertical racks carried by the columns respectively, the pinions mounted on and in fixed relations to the bed and connected with the racks, means for actuating the pinions independently and means for actuating them simultaneously, substantially as set forth.

4. In a mining machine, the combination of the bed frame, the carriage thereon, the cutter frame arranged vertically between the sides of the carriage, the vertical columns for supporting the bed arranged independently of each other, means for securing the columns independently to the floor and to the roof of the mine, means for adjusting the bed vertically upon said columns, and the bed sup-

- porting devices supplemental to the adjusting devices and adapted to be thrown out of action without affecting the bed.
5. In a mining machine, the combination of the bed, 5 the carriage thereon, the vertical supporting devices for the bed, one on each side near the rear thereof, means for adjusting the bed vertically on said supporting devices, supplemental supporting devices at the forward part of the bed adjustably connected therewith independently of 10 the aforesaid vertical supporting devices, and friction clamps supplemental to said adjusting means for securing the bed to the supporting devices, whereby the adjusting devices can be relieved.
6. In a mining machine, the combination of the bed, 15 the carriage thereon, the vertically arranged columns adapted to be secured independently of each other to the roof and the floor of the mine, the racks, the pinions engaging with the racks, means for rotating the pinions to effect the vertical adjustment of the bed, and the friction 20 clamps independent of the adjusting devices for binding the bed to the columns whereby the adjusting devices are relieved, substantially as set forth.
7. In a mining machine, the combination of the bed, 25 the carriage thereon having a cutting apparatus, the vertically arranged columns adapted to be secured to the roof and the floor of the mine, and mechanism for adjusting bodily the bed and the carriage vertically, comprising the racks on the columns, the pinions engaging therewith, the longitudinally arranged shafts for actuating the pinions, 30 and the cross shaft for actuating the longitudinal shafts, said columns being transversely opposite to each other, and independently adjustable relatively to the bed, substantially as set forth.
8. In a mining machine, the combination of the horizontally arranged and laterally extended bed frame, the horizontally extended carriage mounted on and traveling along said bed frame, the vertically arranged chain frame 35 on the carriage, the cutter chain on said frame, the electric motor at the rear end of said carriage, said carriage with the chain frame and motor moving bodily forward and back and changing the position of the center of gravity of the bed frame and the carriage, the vertically arranged columns one on each side of the bed frame, and secured to the roof and the floor of the mine independently of each 40 other, the vertical racks arranged in the transverse vertical plane of the center of gravity of the carriage and of the bed frame when the carriage is in its rearmost position and the pinions mounted on said bed and in engagement with said racks and adapted for adjusting the bed 45 vertically; substantially as set forth.
9. In a mining machine, the combination of the bed, the carriage thereon, the cutter-frame, the vertically arranged support for the bed, the racks and pinions connecting the bed to the vertical support, and two sets of devices for actuating the pinions independently of each other or simultaneously, as desired, substantially as set forth.
10. In a shearing mining machine, the combination of a bed frame, supporting wheels, means for connecting the 50 supporting wheels to the bed frame whereby it can be supported on a track or on the ground, a vertical support for the bed frame, means for adjusting the said frame vertically on the said support, a carriage on the bed frame and an endless cutter on the carriage adapted to make a vertical rectilinear cut while the carriage is held against vertical movement.
11. In a mining machine, the combination of the bed, the carriage thereon, the cutter frame on the carriage, the rear columns, one at each side of the machine, independent 55 of each other and adapted to be secured independently to the roof and the floor of the mine, the front columns secured to the roof and the floor of the mine independent of each other and secured to the front of the bed independently of the rear columns, and means for adjusting the bed frame vertically on the columns, the rear columns being arranged to relieve the front columns of the weight of the machine when the carriage is in its rear position; substantially as set forth.
12. In a mining machine, the combination of the bed, 60 the carriage thereon having the cutter-frame, the vertical
- supports relatively near the rear end of the bed, means for adjusting the bed thereon, the supplemental vertical supports at the front end of the bed, and clamps for securing the front end of the bed to the front vertical supports, said clamps being pivotally connected to the bed, substantially as set forth. 85
13. In a mining machine, the combination of the bed-frame, the carriage thereon having the cutter-frame, the columns M M, the clamps N, the racks O, guiding and actuating means on said carriage having paths extending to the front and rear of said columns, pinions P, the longitudinal shafts p, the cross shaft q geared to the shafts p, and means for rotating the shaft q, substantially as set forth. 90
14. In a mining machine, the combination of the bed, 95 the carriage thereon having the cutter-frame, the columns M, the racks O, the clamps N, the pinions P, the shafts p mounted in the clamps N and also on the bed, and means for rotating the shafts p, substantially as set forth.
15. In a mining machine, the combination of the bed, 100 the carriage thereon having the cutter-frame, the columns M, the racks O, the pinions P, the shafts p, the two-part shaft q, and means for connecting together the two parts of the shaft q, substantially as set forth.
16. In a mining machine, the combination of the bed, 105 the carriage thereon having the cutter-frame, the vertical columns or supports for the rear part of the bed, means for adjusting the bed thereon, and the front columns S having the adjustable clamps connected by hinges or pivots as at t⁴ t⁵ to the bed, substantially as set forth. 110
17. In a mining machine, the combination of a rectangular horizontally arranged bed-frame, a cutter-chain in a vertical plane between the side bars of the bed frame, a carriage on the bed-frame and means for supporting the bed frame at different positions vertically above the ground, a frame for the chain having the side chain guides one above the other, a central longitudinal bar for the chain-frame, a support at the rear of the carriage for the chain-frame, the guide at the front end of the bed for the central bar, and the bars extending upwardly from the bed for supporting the guide, substantially as set forth. 115
18. In a mining machine, the combination of the rectangular bed having substantially parallel side bars adapted to lie in substantially the same horizontal planes, the cutter-chain, the carriage, the frame for the chain having the chain-guides arranged substantially as set forth to have the forward, the downward and the backward moving parts of the chain in the same vertical planes between the side bars of the bed, and having the central supporting bar, the front elevated guide for the chain-frame, an upwardly extended supporting bracket for the rear end of the chain-frame, and means extending horizontally laterally from the chain-frame for connecting it to the supporting bracket, substantially as set forth. 120
19. In a mining machine, the combination of the rectangular bed frame having two substantially parallel side bars adapted to lie in substantially the same horizontal planes, the cutter-chain, the carriage, having a gearing supporting part and a frame for the chain, a horizontal chain-driving shaft, a vertically rotating sprocket wheel thereon, the chain frame having guides which hold the forward-moving, the downward-moving, and the backward-moving parts of the chain in the same vertical planes between the side bars of the bed frame, and having a central thrust-bar mounted in an elevated guide-way supported at the front end of the bed, and a bracket or support for the rear end of the chain frame extending upwardly from the gearing support, substantially as set forth. 125
20. In a mining machine, the combination of a bed-frame, a cutter-chain cutting on vertical lines, a supporting frame for the chain, a motor at the rear of the carriage, a longitudinally arranged shaft geared to the motor, a horizontal transverse shaft in front of the motor gearing, and geared to the longitudinal shaft, and a vertically rotating sprocket wheel in the longitudinal vertical planes of the chain-frame and of the motor whereby a relatively short chain can be employed arranged entirely in front of the motor and substantially all utilized for cutting as described. 130
- 140
- 145
- 150
- 155
- 160

21. In a shearing mining machine, the combination of the bed frame, a carriage movable longitudinally of the bed frame, an endless cutter on the carriage adapted to form an elongated vertical rectilinear slot, a front support for the bed frame adapted to be fastened to the roof and floor of the mine and to support the said frame near its front end, a rear vertical support for the bed frame adapted to be fastened to the roof and floor of the mine, and support the said frame near its rear end, a vertical 10 guide for the rear end of the frame adapted to engage the said rear support and to sustain the weight of the entire machine, and a supplemental guide for the front portion of the machine adapted to engage with said front support and to be thrown out of supporting action independently 15 of the rear guide.
22. In a shearing mining machine, the combination of a rear vertical support adapted to be secured to the roof and to the floor of the mine, a front vertical support adapted to be secured to the roof and floor of the mine independently of said rear support, a bed frame 20 slideable vertically along the said independent supports, a carriage on said bed frame, movable forward and back thereon, a front thrust cutting apparatus having an endless chain arranged to travel in a vertical plane, a chain frame on 25 the carriage having an elongated rectilinear chain supporting guide at the front end adjacent to the line of thrust, a motor at the near end of the carriage, gearing connecting the motor to the cutter chain, and means for raising and lowering the said bed frame arranged to bear upon said 30 frame, substantially in the transverse plane of the center of gravity of the bed, the motor and the carriage.
23. In a shearing mining machine a rear vertical support adapted to be secured to the roof and the floor of the mine, a front vertical support adapted to be secured 35 to the roof and floor of the mine independently of the rear column or support, a bed frame slideable vertically along the said independent supports, means for clamping the bed frame to the vertical supports, said parts being arranged substantially as set forth whereby the supports 40 can be arranged vertically while their lower ends or upper ends are in different horizontal planes, power devices arranged relatively near the rear end of the bed frame for adjusting the bed vertically and sustaining its weight, a carriage on the said bed frame and adapted to move forward and back thereon, an endless cutter chain, a 45 chain supporting frame on the carriage arranged to hold the chain in a vertical plane, a motor at the rear end of the carriage, chain driving gearing actuated by and situated in front of the motor, the rear support and the devices 50 for adjusting the bed vertically being arranged as set forth to receive the weight of the motor when the carriage is in its rear position, substantially as set forth.
24. In a shearing mining machine, the combination of the rear vertical support adapted to be secured to the 55 roof and floor of the mine, the front vertical support, adapted to be secured to the roof and floor of the mine independently of said rear support, a reciprocating carriage having a chain frame comprising an upwardly inclined chain guide, a downwardly inclined chain guide, a vertically arranged chain guide at the front end connecting the divergent ends of the inclined chain guides, and a central thrust bar, the bed frame for the carriage slideable vertically along said independent supports and having a relatively wide support and guide way for the rear end of 60 the carriage and the relatively narrow support and guide way for the central thrust bar of the chain frame, the motor on the carriage, an endless cutter chain on the chain frame, and power transmitting devices interposed between said motor and said chain.
25. In a shearing mining machine, the combination of the rear vertical support adapted to be secured to the roof and floor of the mine, the front vertical support, adapted to be secured to the roof and floor of the mine independently of said rear support, a reciprocating carriage having a chain frame comprising an upwardly inclined chain guide, a downwardly inclined chain guide, a vertically arranged chain guide at the front end connecting the divergent ends of the inclined chain guides, and a central thrust bar, the bed frame for the carriage slideable vertically along said independent supports and having a relatively wide support and guide way for the rear end of the carriage, and the relatively narrow support and guide way for the central thrust bar of the chain frame, the motor on the carriage, an endless cutter chain on the chain frame, power transmitting devices interposed between said motor and said chain, and means for adjusting said bed frame vertically. 70
26. In a mining machine, the combination of a reciprocating carriage having a chain frame arranged vertically between the sides thereof, a cutter chain on the said chain frame adapted to cut an elongated vertical slot, a bed frame for the carriage adapted to support it on both sides of the said chain frame, the vertically arranged supporting devices for the bed frame adapted to be secured to the roof and floor, and means for vertically adjusting the bed 75 80 frame upon the said vertical supporting devices.
27. In a mining machine, the combination of a reciprocating carriage having a chain frame arranged vertically between the sides thereof, a cutter chain on said chain frame adapted to cut an elongated vertical slot, a motor on said carriage, a bed frame for the carriage adapted to support it on both sides of said chain frame and of said motor, the vertically arranged supporting devices for the bed frame adapted to be secured to the roof and floor, and means for vertically adjusting the bed frame upon the 100 105 vertical supporting devices.
28. In a mining machine, the combination of the reciprocating carriage, a chain frame on the carriage, a cutter chain on the said frame adapted to operate at the front end of the machine, a motor secured to the rear end of the carriage, a bed frame for the carriage and a vertical support for the bed comprising two independent columns fastened to the floor and roof, one upon each side of the bed frame, and situated in the transverse plane of the center of gravity of the whole mechanism when the carriage is in its rearmost position. 110 115
29. In a mining machine, the combination of a bed frame, a carriage arranged to move forward and back thereon, a cutter frame movable with the carriage, vertically arranged supports for the bed, one at either side thereof, vertical racks and pinions connecting the bed with the vertical supports to permit the bodily adjustment of the bed vertically, and sets of actuating devices, one for each pinion, each set being independently operable. 120
30. In a mining machine, the combination of the bed, 125 the carriage thereon having the cutter frame, the vertical support relatively near the rear end of the bed, means for adjusting the bed thereon, the supplemental vertical support for the front end of the bed, and means pivotally connected to the bed for securing the front end thereof to the front vertical support.

In testimony whereof, I affix my signature, in presence of two witnesses.

EDWIN R. MERRILL.
